GARMENT HANGER

Filed Oct. 29, 1942

UNITED STATES PATENT OFFICE

2,383,819

GARMENT HANGER

Henry O. Ronning, Minneapolis, Minn., assignor
to Waldorf Paper Products Company, St. Paul,
Minn., a corporation of Minnesota

Application October 29, 1942, Serial No. 463,727

3 Claims. (Cl. 223—87)

My invention relates to garment hangers and has for an object to provide a garment hanger constructed largely of paper.

Another object of the invention resides in providing a garment hanger having a frame constructed with a cross frame member and side frame members connected thereto and separable at their ends and in providing a fastener for the free ends of the side frame members adapted to be constructed of paper or other similar flat stock.

An object of the invention resides in constructing the fastener with a plate-like body provided with at least one tortuous opening therein for the endwise reception of one of the side frame members.

A still further object of the invention resides in constructing the body of the fastener with a shoulder adapted to engage a corresponding shoulder on the frame for securing the fastener to the frame.

A feature of the invention resides in providing a construction for holding said shoulders in engagement.

Another object of the invention resides in forming on the fastener a lug having a shoulder and in constructing the side frame member with a slot for the reception of the lug and forming a shoulder for engagement with the shoulder on the fastener.

Another object of the invention resides in providing on the fastener a finger for engagement with the side frame member to hold the lug within the slot.

Another object of the invention resides in providing a supporting hook for the garment hanger constructed of paper and in further providing fastening means secured to the hook for connecting the free ends of the side frame members of the garment hanger together.

Other objects of the invention reside in the novel combination and arrangement of parts and in the details of construction hereinafter illustrated and/or described.

In the drawing:

Fig. 1 is a perspective view of a garment hanger illustrating an embodiment of my invention.

Fig. 2 is a view similar to Fig. 1 showing the parts partly assembled.

Fig. 3 is an elevational sectional view taken on line 3—3 of Fig. 1 and drawn to a greater scale.

Fig. 4 is an elevational sectional view taken on line 4—4 of Fig. 3 and drawn to a lesser scale.

My invention comprises a frame indicated in its entirety by the reference numeral 11 on which the garments are supported and a supporting member 12 for supporting the garment hanger on a hook, rod, or other suitable support. These parts will now be described in detail.

The frame 11 consists of a cross frame member 13 and side frame members 14 and 15 hingedly

connected therewith. The frame members 14 and 15 are separable at their outer ends and are adapted to swing from an extended position such as shown in Fig. 1 to a collapsed position in which the said frame members all overlie one another. The frame 11 is preferably constructed from paper which is formed U-shaped in cross-section to provide each of said frame members with a web 36 and flanges 37 extending outwardly therefrom. The stock from which the frame 11 is constructed is scored transversely to provide hinges 16 between the frame members 14 and 15 and the frame member 13. Frame 11 is preferably constructed as disclosed in the patent to Reynolds 15 Guyer et al., No. 2,164,207, issued June 27, 1939.

The supporting member 12 is constructed from a blank formed from a sheet of heavy paper or paper board and comprising a fastener 18 having a hook 19 connected thereto and integral therewith. The hook 19 has a hook portion 21 adapted to be hooked over a rod or other supporting structure and a shank 22 which connects the same to the fastener 18. The fastener 18 has a body 23 of appreciable width at the lowermost portion thereof and by means of which the fastener is secured to the side frame members 14 and 15.

The following construction is employed for securing the fastener 18 to the side frame members 14 and 15 and is best shown in Figs. 2 and 4. Inasmuch as the construction employed for each side member is identical, only that used in conjunction with the frame member 15 will be described in detail. This construction utilizes an elongated opening 24 formed in the body 23 of

fastener 18 which extends through the edge 25 thereof as indicated at 26, leaving said opening open at its outer end. A similar opening 27 is formed on the opposite side of the body 23 which serves a purpose similar to that of opening 24.

These openings terminate short of one another to provide a butt 28 and a neck 29 between said openings which neck connects the butt with the portion of the body 23 from which the hook 19 issues. On the butt 28 is formed a lug 31 which

45 has a transversely extending shoulder 32 on the upper end thereof. Opposite the lug 31, the opening 24 is constructed with a bight 33. The opening 24 provides in the portion of the body 23 above the butt 28 a finger 34 which is spaced from the butt 28 and which lies opposite a small depression 35 in said butt. The opening 27 is of exactly the same form as the opening 24.

The web 36 of the side frame member 15 is constructed at its end with a longitudinally extending notch 38 of a width slightly greater than the thickness of the stock from which the supporting member 12 is constructed. The said web of the frame member 15 is also constructed with a slot of the same width as the notch 38 which is in alignment with said slot and spaced there-

from to leave a connecting portion 41 between said slot and notch. The upper end of the slot 39 forms on said connecting portion 41 a transverse shoulder 42 which will presently be described in detail. The side frame member 14 of the frame 11 is constructed in the same manner as the frame member 15.

The method of assembling the garment hanger is as follows: Either frame member 14 or 15 may first be applied to the fastener 18. In the drawing, side frame member 14 has been illustrated as applied and since method of application is the same for both side frame members, the description of the method will be limited to side frame member 15. The free end of the side frame member 15 is inserted into the open ends 26 of the opening 24 with the notch 38 in the plane of the supporting member 12. The parts are then forced together in the direction of extent of the side frame member 15. As the parts move, the connecting portion 41 travels along the opening 24 following the tortuous passageway formed thereby. As the finger 34 reaches the portion 43 of the web 36 of frame member 15 immediately below the slot 39, the parts become sprung or bent and the connecting portion 41 is forcefully passed over the lug 31 which is provided with a cam surface 44 for facilitating such movement. As the movement of the parts progresses, the neck 29 of the body 23 of the supporting member 12 becomes received in the notch 38. When the connecting portion 41 reaches the innermost end 45 of the opening 24, the slot 39 registers with the lug 31 and said lug becomes received within said slot. When so disposed, the two shoulders 32 and 42 engage one another and prevent longitudinal relative movement between the side frame member 15 and the fastener 18. In such position, the finger 34 bears down upon the portion 43 of web 36 and holds the lug 31 within the slot 39. The parts are then arranged as shown in Fig. 1. It will readily be comprehended that each of the side frame members 14 and 15 are separately attached to the fastener 18 and when both of them are attached, the garment hanger appears as in Fig. 1. For the purpose of illustration, the side frame member 14 has been shown attached to the fastener 18 in Fig. 2, while the side frame member 14 is shown in position to be applied to the said fastener.

If it becomes desirable to disconnect the fastener 18 from the frame members of the garment hanger, the same may be accomplished by twisting the side frame member to be detached, until it lies in a plane parallel to the plane of the supporting member 12. This will straighten out one of the flanges of the side frame member and also offset the finger of the fastener cooperating with said frame member. In this position the lug of the fastener can be disengaged from the slot in the side frame member and the two parts disconnected.

The advantages of my invention are manifest. The garment hanger can be entirely constructed from materials other than metals, whereby a depletion of the metals of the country may be avoided. By means of the construction shown, the supporting member and particularly the hook thereof is rigidly held with reference to the frame of the garment hanger so that the loaded garment hanger may be grasped by one of the frame members and readily disconnected from the sup-

port on which the hook is hooked. The invention can be constructed at a nominal expense and by means of equipment readily available for the purpose. The parts may be readily and easily assembled and when in position, are securely held from disengagement. A garment hanger constructed in accordance with my invention is rigid and substantial and will readily support the garments carried thereby.

Changes in the specific form of my invention, as herein described, may be made within the scope of what is claimed without departing from the spirit of my invention.

Having described my invention, what I claim as new and desire to protect by Letters Patent is:

1. A garment hanger comprising a frame including a cross frame member and converging side frame members connected thereto and separable at their ends, a fastener including a plate-like body having an elongated opening extending through an edge thereof for the endwise reception of one of said side frame members, said opening forming in said body a lug having a shoulder extending across said opening and a recess opposite said lug forming a bight in said opening, the denoted side frame member having a longitudinally extending slot therein for the reception of said lug and forming a transversely extending shoulder for engagement with the shoulder on said lug, said side frame member bending in its passageway through said bight, and straightening when the slot registers with the lug to cause the lug to be received within the slot and means for attaching said other side frame member to said fastener.

2. A garment hanger comprising a frame including a cross frame member and converging side frame members connected thereto and separable at their ends, a fastener including a plate-like body having an elongated opening extending through an edge thereof for the endwise reception of one of said side frame members, said opening forming in said body a lug having a shoulder extending across said opening and facing toward the end of the frame member, the denoted side frame member having a longitudinally extending slot therein falling short of the end of said frame member for the reception of said lug and forming a transversely extending shoulder facing away from the end of the frame member for engagement with the shoulder on said lug, and means for attaching said other side frame member to said fastener.

3. A garment hanger comprising a frame including a cross frame member and converging side frame members connected thereto and separable at their ends, a fastener including a plate-like body having an elongated opening extending through an edge thereof for the endwise reception of one of said side frame members, said opening forming in said body a lug having a shoulder extending across said opening, the denoted side frame member having a longitudinally extending slot therein for the reception of said lug and forming a transversely extending shoulder for engagement with the shoulder on said lug and a finger on said fastener on the side of said opening opposite said lug for holding said side frame member with the lug received in the slot thereof, and means for attaching said other side frame member to said fastener.
